MINE HOIST CONTROL

James E. Borland, Wilkinsburg, Pa., assignor to
Westinghouse Electric & Manufacturing Company,
East Pittsburgh, Pa., a corporation of
Pennsylvania

Application December 26, 1942, Serial No. 470,283

10 Claims. (Cl. 254—173)

My invention relates to a system of control for motors and, more particularly, to direct current motors for operating hoists.

In the operation of mine hoists, many safety devices are needed and among them are the brakes. These brakes are usually operated—released—by fluid pressure and simple very reliable mechanical means are used to set the brakes. With existing equipment, the brake release levers may be left in the non-release position, thus preventing the operation of the motor while the motor may be continuously energized to exert a torque.

One broad object of my invention is the provision of deenergizing a motor tending to operate hoist equipment if the brakes remain unreleased.

A more specific object of my invention is to positively require an attendant to release the brakes in a hoist equipment at the proper time to be able to proceed with the hoisting operation.

Another object of my invention is to deenergize both the motor and generator fields in a Ward-Leonard type of control if the motor armature is prevented from rotating as by means of a brake.

The objects specifically stated are merely illustrative. Many other objects and advantages will, no doubt, become more apparent from a study of the following specification and the drawing made part thereof.

In the drawing, the single figure is a diagrammatic showing of my contribution to the art as applied to a mine hoist.

In the figure, P designates a prime mover for operating a generator G and exciter E. The generator G and the exciter are disposed to supply energy to the hoist motor M. The hoist motor is shown coupled to a pair of hoist drums operating loads such that one load moves up when another load moves down.

A suitable braking system B is provided for the hoist drums 37 and 38 and all the usual safety equipment and control equipment is used. I show only so much of this equipment as is helpful in presentation of my invention.

The best understanding of my contribution to the art may no doubt, be had from a study of the operation of the control.

The operation will be apparent from the following:

In the drawing, the equipment is shown not in operation. If the hoist is to be operated, the prime mover P is started and switches S, and other switches no part of this invention and not 55

shown, are operated to closed position. The hoist motor M is thus connected to the main generator G.

The controller C must be in the "off" position, as shown, otherwise, no operation of the hoist can be effected. This is one feature of my invention, the importance of which will appear later.

When the speed of the prime mover P is up to full value, the voltage of the exciter E will be normal and as a consequence a circuit is established from bus 1, through segments 2 and 3 of the controller C, switches 4 and 5, the coil 6 of the time limit relay 7, the back contactors 8 and 9 of the directional contactors 10 and 11 to bus 12.

The time limit relay immediately closes its contact members 13 whereupon a circuit is established from the energized switch 5 through the safety equipment, closed contact member 13 of the time limit relay 7, through the parallelly connected coils 14 and 15 of the low voltage relay 16 and brake control contactor 17, respectively, to bus 12.

The low voltage relay closes its contact members 18 to hold itself in regardless of the position of the controller C. The operation of control contactor 17 closes the contact members 19 and 20. Closure of contact members 19 closes an energizing circuit, from the energized safety equipment to bus 12, for coil 21 of the field contactor FC. An instant later contact members 22 and 23 are closed to thus energize the motor field 24. Since contact members 20 are already closed, the parallelly connected brake release coils 25 and 26 are energized and valves 27 and 28 are thus closed. The circuit for these coils 25 and 26 may be traced from bus 1 through contact members 22 and 20, coils 25 and 26, contact members 23 to bus 12.

By the closure of valves 27 and 28, the conduit connection through these valves from the region below the brake setting weights W₁ and W₂ to the low pressure side of the hydraulic, or pneumatic, brake system B, is closed. It is now possible to release the brakes by the normal operation of the brake release levers 29 and 30.

Many hoisting operations require that power be applied to the hoist motor for a short period at the start of each hoisting cycle, before releasing the brakes holding the cable winding drums. This has the advantage that the load at no instant starts to descend just before it is to be hoisted. For those applications where this method of starting is not necessary, the brake levers

29 and 30 may be set to release the brake, without changes, before the controller C is operated to an operating position.

Assuming that the motor M is to apply a hoisting torque before the brakes are released, then the attendant operates the controller to the first hoisting, or raise, position. Immediately a circuit is established from energized segment 31 of the controller C through segment 32, coil 33 of the directional contactor 10 to bus 12.

Operation of the directional contactor 10 causes the energization of generator field 34 in such a direction as to tend to hoist, say, the load on cable 35 and tend to lower the load on cable 36. The attendant then operates the brake levers 29 and 30 to release the drums 37 and 38. Briefly this proceeds as follows: Operation of the levers 29 and 30, clockwise and counter-clockwise respectively, supplies fluid pressure below the weights W_1 and W_2 to raise these weights, whereby the brakes on the drums are released. Since the motor is already exerting a hoisting torque, the load is immediately picked up and the hoisting proceeds.

The time limit relay 7 has a time constant of several seconds. The time of its operation is adjustable by the spring means shown or in some other manner. Any kind of adjustable time limit device may be used.

The instant directional contactor 10 has operated contact members 8 open to deenergize coil 6. After a predetermined time interval contact members 13 open. If the brakes have been satisfactorily released during the period of the time limit relay, the switches 39 and 40 are closed and the hoisting proceeds as desired, but if the attendant delays the releasing of the brakes too long, the contact member 13 opens before switches 39 and 40 are closed and in consequence the low voltage relay 16 is deenergized to open contact member 18. All the control circuits are thus deenergized. This means that the brakes remain set even though an instant too late the valves 41 and 42 are operated to supply fluid pressure to the region below the weights W_1 and W_2 . This is so because valves 27 and 28 are opened by the deenergization of coils 25 and 26 to release any fluid pressure that might tend to develop below the weights W_1 and W_2 . This is an important contribution to the art. The attendants are thus, by the characteristics of my equipment, trained to proceed with the requisite dispatch when a hoisting operation is to be effected. This contribution is by no means the only one nor the most important one.

In direct-current variable voltage mine hoist equipment, it sometimes happens that the hoist motor is damaged by an operator who, either through carelessness or through inadvertence, may leave the controller in some operating position while the brake levers are not in the brake release position. Under such conditions, a large circulating current may flow in the hoist generator-hoist motor armature circuit, sufficient to overheat the motor armature, which would remain at a standstill, or to distort the commutator, by local heating under the brushes, or both.

If during operation when the controller is in any one of its operating positions, whether hoisting or lowering, and one or the other or both the brake levers are not in proper position either or both of the switches 39 and 40 will be open and since the contact members 13 of the time limit relay are open the control circuits will be deenergized because the energizing circuits for

coils 14 and 15 are opened. The operator, or attendant, thus loses control and must reset the controller to the "off" position and start all over. If he still has not properly set the levers 29 and 30 and he proceeds to start the hoist equipment by moving the controller to one of its operating positions, the time limit relay will, by holding contact members 13 closed for a short time, merely permit the application for a short time of a torque on the motor. My invention thus does not permit of any operation that might damage the hoist motor.

The benefits of my invention are also obtained when only one drum is to be operated. If only drum 37 is to be operated, the attendant operates clutch lever 43 to declutch drum 38 from shaft 44 and to close switch 45. Now it is still necessary to properly position lever 29 before proper operation of drum 37 may proceed.

The same, of course, holds true if drum 38 only is to be used. In this case, clutch lever 46 is operated to declutch drum 37 from shaft 44 and switch 47 is closed. Now lever 30 must be in the correct position before the operation may proceed properly. If the equipment is of the type using only one drum fixed to the shaft then the clutch switches are not needed and only one brake lever switch is needed. The circuit needed would be one equivalent to an open circuit at switches 45 and 47 and a closed circuit at switch 39, when the switch 40 represents the one controlled by the single brake lever.

From the foregoing it will be apparent that I have thus provided a substantially "fool-proof" control scheme, but I do not wish to be limited to the particular showing made but wish to be limited only by the claims hereto appended.

I claim as my invention:

1. In a control for a hoist, in combination, a hoist drum, a motor for operating the drum, braking mechanisms for, as desired, either holding the drum or releasing it, a brake lever for effecting release of the brake, a normally open brake lever switch that is closed only when the brake lever is actuated to release the brake, a directional contactor for causing the operation of the motor in a given direction, back contact members normally closed when the directional contactor is not actuated, said contact members being connected in parallel to the brake lever switch, a controller having an off position and a plurality of operating positions, electromagnetic motor stopping means connected in series with the parallel circuit of said back contact members and brake lever switch whereby either the back contact members or the brake lever switch must be closed to energize said electromagnetic means, said controller having switching means closed in the off position to energize said electromagnetic means and having switching means for energizing said directional contactor to open its back contact members when in any one of its operating positions, whereby said electromagnetic means is deenergized unless the brake lever switch is closed when said controller is in its operating positions.

2. In a control for a hoist, in combination, a hoist drum, a motor for operating the drum, braking means for, as desired, either holding the drum or releasing it, a brake lever for effecting, when in one position, release of the brake, and when in a second position, setting of the brake, brake lever switching means closed when the lever is in its said one position and open when it is in its said second position, a contactor when

energized causing the motor to operate, said contactor having back contact members, that are normally closed when the contactor is deenergized, said back contact members being connected in parallel to the brake lever switching means, electric means which, when deenergized, effect the stopping of said motor, said electric means being connected in series with the parallelly connected back contact members and brake lever switching means, whereby said electric means become deenergized if both the brake lever switching means and contact members are open, a controller having an off position and an on operating position for energizing said electric means, said controller effecting the energization of said contactor only in said operating position whereby the back contact members are opened, the function thus being, if the brake lever switching means are not closed, to deenergize said electric means to thus deenergize the motor.

3. In a control for a hoist, in combination, a hoist drum, a motor for operating the drum, braking means for, as desired, either holding the drum or releasing it, a brake lever for effecting, when in one position, release of the brake, and when in a second position, setting of the brake, brake lever switching means closed when the lever is in its said one position and open when it is in its said second position, a contactor when energized causing the motor to operate, said contactor having back contact members that are normally closed when the contactor is deenergized, said back contact members being connected in parallel to the brake lever switching means, electric means which, when deenergized, effect the stopping of said motor, said electric means being connected in series with the parallelly connected back contact members and the brake lever switching means; whereby said electric means become deenergized when both the brake lever switching means and the contact members are open, a clutch for disconnecting the drum from the motor, a clutch lever, clutch lever switching means closed when said drum is declutched from the motor, said clutch switching means being disposed in parallel to the back contact members and brake lever switching means, a controller having an off position and an operating position for energizing said electric means, said controller effecting its energization of said contactor only in said operating position whereby the back contact members are opened, the function thus being, if the brake lever switching means and the clutch lever switching means are both open, to deenergize said electric means to stop the motor, or to operate the motor independently of the brake lever switching means if the clutch lever switching means is closed.

4. In a control for a hoist, in combination, a hoist drum, a motor for operating the drum, braking means for, as desired, either holding the drum or releasing it, a brake lever for effecting, when in one position, release of the brake, and when in a second position, setting of the brake, brake lever switching means closed when the lever is in its said one position and open when it is in its said second position, a contactor when energized causing the motor to operate, said contactor having back contact members that are normally closed when the contactor is deenergized, said back contact members being connected in parallel to the brake lever switching means, electric means which, when deenergized, effect the stopping of said motor, said electric means being

connected in series with the parallelly connected back contact members and brake lever switching means, whereby said electric means become deenergized if both the brake lever switching means and contact members are open, a time limit device having switching means that remain closed for a short time after the time limit means becomes deenergized, said time limit switching means being disposed in parallel to the back contact members and brake lever switching means whereby said electric means remain energized for a short time even though both said back contact members and brake lever switching means are opened, a controller having an off position and an operating position for energizing said electric means, said controller effecting the energization of said contactor and the deenergization of said time limit device only in said operating position whereby the back contact members and a short time thereafter the time limit switching means are opened, the function thus being, if the brake lever switching means are not closed prior to the end of the short time, to deenergize said electric means to thus deenergize the motor.

5. In a control for a hoist, in combination, a hoist drum, a motor for operating the drum, braking means for, as desired, either holding the drum or releasing it, a brake lever for effecting, when in one position, release of the brake, and when in a second position, setting of the brake, brake lever switching means closed when the lever is in its said one position and open when it is in its said second position, a contactor when energized, causing the motor to operate, said contactor having back contact members that are normally closed when the contactor is deenergized, said back contact members being connected in parallel to the brake lever switching means, electric means which, when deenergized, effect the stopping of said motor, said electric means being connected in series with the parallelly connected back contact members and the brake lever switching means, whereby said electric means become deenergized when both the brake lever switching means and the contact members are open, a clutch for disconnecting the drum from the motor, a clutch lever, clutch lever switching means closed when said drum is declutched from the motor, said clutch switching means being disposed in parallel to the back contact members and brake lever switching means, a time limit device having switching means disposed in parallel to the back contact members, the brake lever switching means, and the clutch lever switching means, and operable to remain closed for a short time after the time limit device becomes deenergized, whereby said electric means remains energized for a short time if all the other switching means of the mentioned parallel connections are open, a controller having an off position and an operating position for energizing said electric means, said controller effecting the energization of said contactor and the deenergization of said time limit device only in said operating position whereby the back contact members are opened and a short time thereafter the time limit switching means is opened, the function thus being, if the brake lever switching means and the clutch lever switching means are both open, to deenergize said electric means to stop the motor at the end of the short time, or to operate the motor independently of the brake lever switching means if the clutch lever switching means is closed.

6. In a system of control for a hoist, in combination, a motor, a hoist drum operated by the motor, a brake, a brake lever for effecting the release and setting of the brake depending on the position of the brake lever, a controller operable, when not in its off position, to energize the motor, a source of supply, a control circuit connected to the source of supply, said circuit including, a controller switch, closed only when the controller is in the off position, and an electromagnetic coil operated switch, closed only when the coil is energized, said controller switch and electromagnetic coil operated switch being connected in parallel with each other and in series with the coil of the coil operated switch, and a controller operated switch, closed only when the controller is in the off position, and a brake lever switch, closed only when the brake is released, said controller operated switch and brake lever switch being connected in parallel with each other and also connected in series with the coil of the coil operated switch, said circuit also including switching means for stopping the energization of the motor when the coil of the coil operated switch becomes deenergized.

7. In a system of control for a hoist, in combination, a suitably operated generator, having a generator field winding, a motor, having a motor field winding, connected to the generator to be operated thereby, a hoist drum, operated by said motor, a brake, a brake lever for setting the brake to hold the drum or release it depending on the position of the brake lever, a source of direct current power, an electromagnetically operable switch for connecting the source of power to the motor and generator field windings when the electromagnet of the electromagnetically operable switch is energized and for disconnecting the motor and generator field windings when said electromagnet is deenergized, control circuits disposed to be connected to the source of direct current, said control circuits including, a controller having an off position and at least one operating position, a control contactor having an actuating coil and contact members that are closed only when the actuating coil is energized, switching means, connected in parallel with said contact members, and thus comprising a first parallel circuit, said switching means being controlled by the controller and in closed circuit condition only when the controller is in the off position, a second parallel circuit comprising second switching means, and a brake lever switch, connected in parallel, said second switching means being subject to the control of said controller and being closed only when said controller is in the off position, said brake lever switch being closed only when the brake lever is in position to release the brake, said actuating coil of the control contactor and said two parallel circuits all being connected in series to said source of direct current, and means responsive to the opening of the contact members of the control contactor for deenergizing said electromagnetically operable switch.

8. In a system of control for a hoist, in combination a suitably operated generator, having a generator field winding, a motor having a motor field winding connected to the generator to be operated thereby, a hoist drum, a clutch and lever therefor, which lever, when in one position, clutching the drum to the motor shaft to thus be operated thereby and when in another position declutching the drum from the shaft, a brake, a brake lever for setting the brake to hold the

drum or release it depending on the position of the brake lever, a source of direct current power, an electromagnetically operable switch for connecting the source of power to the motor and generator field windings when the electromagnet of the electromagnetically operable switch is energized and for disconnecting the motor and generator field windings when said electromagnet is deenergized, control circuits disposed to be connected to the source of direct current, said control circuits including, a controller having an off position and at least one operating position, a control contactor having an actuating coil and contact members that are closed only when the

actuating coil is energized, switching means, connected in parallel with said contact members, and thus comprising a first parallel circuit, said switching means being controlled by the controller and in closed circuit condition only when the controller is in the off position, a second parallel circuit comprising second switching means, a brake lever switch, and a clutch lever switch connected in parallel, said second switching means being subject to the control of said controller and being closed only when said controller is in the off position, said brake lever switch being closed only when the brake lever is in position to release the brake and said clutch lever switch being closed only when the clutch lever is in a position to declutch the hoist drum from the motor shaft, said actuating coil of the control contactor and said two parallel circuits all being connected in series to said source of direct current, and means responsive to the opening of the contact members of the control contactor for deenergizing said electromagnetically operable switch.

9. In a system of control for a hoist, in combination, a suitably operated generator, having a generator field winding, a motor, having a motor field winding, connected to the generator to be operated thereby, a hoist drum, a brake, a brake lever for setting the brake to hold the drum or release it depending on the position of the brake lever, a second brake, a second hoist drum, a second brake lever for setting the brake to hold the second hoist drum or release it depending on the position of the second brake lever, a source of direct current power, an electromagnetically operable switch for connecting the source of power to the motor and generator field windings when the electromagnet of the electromagnetically operable switch is energized and for disconnecting the motor and generator field windings when said electromagnet is deenergized, control circuits disposed to be connected to the source of direct current, said control circuits including, a controller having an off position and at least one operating position, a control contactor having an actuating coil and contact members that are closed only when the actuating coil is energized, switching means, connected in parallel with said contact members, and thus comprising a first parallel circuit, said switching means being controlled by the controller and in closed circuit condition only when the controller is in the off position, a second parallel circuit comprising second switching means, and in parallel therewith, two series connected brake lever switches coupled to the respective brake levers, said second switching means being subject to the control of the controller and being closed only when the controller is in the off position and said brake lever switches being closed only when the respective levers to which they are coupled are

in brake releasing positions, said actuating coil of said control contactor and said two parallel circuits all being connected in series to said source of direct current, and means responsive to the opening of the contact members of the control contactor for deenergizing said electromagnetically operable switch.

10. In a system of control for a hoist, in combination, a suitably operated generator, having a generator field winding, a motor having a motor field winding connected to the generator to be operated thereby, a hoist drum, a clutch and lever therefor, which lever, when in one position, clutching the drum to the motor shaft to thus be operated thereby and when in another position declutching the drum from the shaft, a second hoist drum, a clutch and lever therefor, which lever, when in one position clutching the second drum to the motor shaft to thus be operated thereby and when in another position declutching the drum from the shaft, a brake for said drum, a brake lever for setting the brake to hold the drum or release it depending on the position of the brake lever, a second brake, a second brake lever for setting the brake to hold the second hoist drum or release it depending on the position of the second brake lever, a source of direct current power, an electromagnetically operable switch for connecting the source of power to the motor and generator field windings when the electromagnet of the electromagnetically operable switch is energized and for disconnecting the motor and generator field windings when said electromagnet is deenergized, control circuits

disposed to be connected to the source of direct current, said control circuits including, a controller having an off position and at least one operating position, a control contactor having an actuating coil and contact members that are closed only when the actuating coil is energized, switching means, connected in parallel with said contact members, and thus comprising a first parallel circuit, said switching means being controlled by the controller and in closed circuit condition only when the controller is in the off position, a second parallel circuit comprising second switching means, and connected in parallel therewith one sub-parallel circuit including a brake lever switch coupled to the first brake lever and a clutch lever switch coupled to the first clutch lever, and a second sub-parallel circuit including a second brake lever switch coupled to the second brake lever and a second clutch lever, said second switching means being subject to the controller and being closed only when the controller is in the off position, and said brake lever switches and clutch lever switches being closed only when the respective levers to which they are coupled are in positions respectively to release the brakes and declutch the drums, said actuating coil of said control contactor and said first and second parallel circuits all being connected in series to said source of direct current, and means responsive to the opening of the contact members of said control contactor for deenergizing said electromagnetically operable switch.

JAMES E. BORLAND.
